INVENTOR
BY Victor J. Evans
ATTORNEY

UNITED STATES PATENT OFFICE.

GROVER C. ALLEN, OF DETROIT, MICHIGAN.

BULB HOLDER.

Application filed April 18, 1922. Serial No. 555,531.

To all whom it may concern:

Be it known that I, GROVER C. ALLEN, a citizen of the United States, residing at Detroit, in the county of Wayne and State of Michigan, have invented new and useful Improvements in Bulb Holders, of which the following is a specification.

This invention relates to bulb holders particularly designed for facilitating the placing or removal of electric lamp bulbs from sockets which are relatively high or out of reach of the average person, and an object of the invention is to provide a bulb holder which embodies a novel form of mechanism for rotating an electric light bulb either screw it into or unscrew it from its socket.

More particularly, the present invention embodies an improvement over my bulb holder as disclosed in the application filed March 18, 1921, Serial No. 453,222, the present invention embodying means for rotating the feed screw which controls operation of the gripping fingers embodied in the bulb holder of the above mentioned application.

A further object of the invention is to provide means whereby the bulb holder may be rotated in either direction by operation of a lever, and it further embodies suitable means for controlling the direction of rotation of the bulb holder for either screwing a bulb into or unscrewing it from its socket.

Other objects of the invention will appear in the following detailed description taken in connection with the accompanying drawings wherein:

Fig. 1 is an edge elevation of the improved bulb holder.

Fig. 2 is a side elevation of the bulb holder.

Fig. 3 is a longitudinal section on the line 3—3 of Fig. 1.

Fig. 4 is a vertical section taken on the line 4—4 of Fig. 3.

Fig. 5 is a horizontal section taken on the line 5—5 of Fig. 3.

Fig. 6 is a fragmentary horizontal section through the bulb holder.

Referring more particularly to the drawings, the improved mechanism disclosed in the present application is designed to be associated with the bulb holder structure disclosed in my application filed March 18, 1921, Serial No. 453,222, which application discloses a bulb holder embodying a body 1 which carries a feed screw 2 rotatable by the

knurled nut 3 for operating suitable bulb gripping fingers, not shown in the present application. In the above mentioned application, the feed screw is rotatable manually and owing to its close proximity to the bulb gripping fingers, it is difficult to use the device in connection with bulbs which are positioned at a relatively great height and with the present mechanism, means is provided for rotating the feed screw from a point remote from the knurled nut 3 so as to permit the removal or replacing of electric light bulbs, from a relatively high place, without the use of a stepladder or other support.

The improved features of the bulb holder, comprises a casing 10 which is cylindrical in shape and is attached to a suitable supporting handle 11 by a forked support 12, the said fork being pivotally connected to the casing 10 by bolts 14 and 15 respectively. A collar or sleeve 16 is mounted about the bolt 15 and a similar bolt or set screw 17 is threaded therein from the opposite end of the sleeve, as clearly shown in Fig. 3 of the drawings. The sleeve 16 provides a bearing for the bevel gear 18, which has a relatively large hub 19 upon which a ratchet 20 is mounted. A lever 21 is provided, which lever projects through a slot 22 in the casing 10 and has a cord, rod or analogous structure 23 connected thereto and extending in close proximity to the hand grip end of the handle 11 to permit free rocking of the lever 21 from the end of the handle 11 remote

from the casing 10. The lever 21 extends about the ratchet 20 and has a pawl 24 pivotally carried thereby as shown at 25 which pawl is adapted for cooperation with the peripheral teeth of the ratchet 20, for rotating the bevel gear 18. A flat spring 26 is carried by the arcuate end 27 of the lever 21 and engages the pawl for urging it into engagement with the perimeter of the ratchet 20, and a spring 28 is connected to the casing 10 and to the lever 21 for returning the lever to its upper position after operation, to permit continued step by step rotation of the bevel gear 18. Bevel gears

29 and 30 mesh with the bevel gear 18 upon opposite side of its axis and these bevel gears carry pawls 31 and 32 respectively which are adapted to cooperate with ratchets 32' and 33, which are pinned to the axial shaft 34.

The axial shaft 34 is provided with a longitudinally extending threaded recess 35

which receives the feed screw 2 so that rotation of the shaft 34 will move the feed screw 2 longitudinally for operating the bulb gripping arms as disclosed in my companion application previously referred to. A sleeve 36 is slidably mounted upon the axial shaft 34 and has a collar 37 formed thereon intermediate its ends, which collar engages in the forked end 38 of the lever 39. The lever 39 is pivotally mounted intermediate its ends and projects through a slot 40 in the casing 10. The ratchets 32' and 33 each have cams 42 thereon which are adapted to be engaged by the rounded heads 43 on the sleeve 36 for moving the pawls 32 upon their pivots to move them out of engagement with their respective ratchets 32' and 33, so as to control the direction of rotation of the shaft 34.

20 For example when the sleeve 36 is positioned as shown in Fig. 3 of the drawings, the pawl 32 is held out of engagement with the ratchet 33 which will permit the bevel gear 30 to rotate when rotating the ratchet, whereas the pawl 31 is in engagement with the ratchet 32' so that rotation of the bevel gear 29 will rotate the shaft 34. When the sleeve 36 is shifted to force the pawl 31 out of engagement with the ratchet 32', the flat 30 spring 45 which engages the respective pawls will force the pawl back into engagement with its ratchet, causing rotation of the shaft 34 in the reversed direction, by rotation of the bevel gear 19.

35 Suitable bearings as shown at 46 are provided, for rotatably supporting the axial shaft 34 and a suitable sleeve construction 47 is provided for connecting the operating mechanism to the body 1.

40 It will be apparent, from the foregoing description, that the body 1 may be positioned to extend longitudinally with the handle 11 or transversely thereto, as shown in dotted lines in Fig. 2 of the drawings, 45 depending upon the location or position of the electric light bulb to be replaced.

It is, of course, to be understood that the invention may be constructed in other manners and the parts associated in different 50 relations and, therefore, I do not desire to be limited in any manner except as set forth in the claims hereunto appended.

Having thus described my invention what I claim is:

55 1. In a lamp bulb holder, the combination with a feed screw, of means for operating said feed screw, and releasable means for controlling the direction of movement of said feed screw.

60 2. In a lamp bulb holder, the combination, with a feed screw, of a lever, means operated by said lever for rotating said feed screw and moving it longitudinally, and means controlling the operation of said feed

screw by said lever for regulating the direction in which the feed screw is moved by operation of the lever.

3. In a device as set forth, the combination with a feed screw, of a shaft connected thereto for operating the feed screw, ratchets carried by the shaft, means cooperating with said ratchets for rotating the shaft, and shiftable means for controlling operation of said ratchets for regulating the direction of rotation of the shaft.

4. In a device as set forth, the combination with a feed screw, of an operating shaft therefor, ratchets carried by said shaft, bevel gears rotatable in opposite directions, pawls carried by said bevel gears for co-operation with said ratchets to rotate said shaft by rotation of the bevel gears, means for forcing said pawls out of cooperative engagement with their respective ratchets, and means for rotating said bevel gears.

5. In a device as set forth, the combination with a feed screw, of an operating shaft therefor, ratchets carried by said shaft, bevel gears rotatable in opposite directions, pawls carried by said bevel gears for cooperation with said ratchets to rotate said shaft by rotation of the bevel gears, means for forcing said pawls out of cooperative engagement with their respective ratchets, a bevel gear meshing with said first named bevel gears, 95 a ratchet carried thereby, and a lever having pawl connection with said ratchet for rotating said last named bevel gear.

6. In a device as set forth, the combination with a feed screw, of an operating shaft therefor, ratchets carried by said shaft, bevel gears rotatable in opposite directions, pawls carried by said bevel gears for cooperation with said ratchets to rotate said shaft by rotation of the bevel gears, a sleeve slidable upon said shaft, a pivotal lever for sliding said sleeve for forcing said pawls out of cooperative engagement with their respective ratchets, and means for rotating said bevel gears.

7. A lamp bulb holder comprising a feed screw, means for rotating said feed screw and moving it longitudinally, and releasable means for controlling the direction of movement of the feed screw.

8. A lamp bulb holder comprising a rotatable housing, a feed screw carried by the housing, means for rotating said feed screw about an axis transversely of the axis of the housing, and means controlling the operation of the feed screw by said last named means for regulating the direction in which the feed screw is moved by operation of the lever.

In testimony whereof I affix my signature.

GROVER C. ALLEN.
